UNITED STATES PATENT OFFICE.

FRANCIS M. BRINCKERHOFF, OF ENGLEWOOD, NEW JERSEY, ASSIGNOR TO THE ELLCON COMPANY, OF NEW YORK, N. Y., A CORPORATION OF NEW YORK.

CAR-FLOOR.

1,178,210.

Specification of Letters Patent.

Patented Apr. 4, 1916.

Application filed September 15, 1914. Serial No. 861,761.

To all whom it may concern:

Be it known that I, FRANCIS McFARLAN BRINCKERHOFF, a citizen of the United States, and a resident of the city of Englewood, Bergen county, State of New Jersey, have invented new and useful Improvements in Car-Floors, of which the following is a specification.

This invention relates broadly to railway car construction and particularly to a floor adapted for railway cars.

The principal object of this invention is to provide a construction adapted for use as a floor, partition, or side wall of a steel car.

A more specific object of this invention is the production of a car floor or car wall adapted to resist the transmission of heat between its opposite surfaces. To accomplish this, I insert a continuous diaphragm of heat insulating material between the steel supporting member with its filling material, and the upper hard wearing surface, thus tending to prevent the transmission of heat through the floor or wall construction.

Another object of this invention is to provide a fire proof car floor capable of withstanding stress and vibration without separating the component parts thereof.

Another object of this invention is to provide a car floor with a relatively inelastic wear surface supported upon a relatively elastic sub-strata adapted to cushion shocks and stresses.

A further object of this invention is to construct a car floor, or side wall, of fire proof material having a composition wear surface wherein the component parts interlock and are secured together to withstand stress and vibration without damaging or separating the various elements thereof.

A still further object of this invention is to produce a self-sustaining car wall or floor structure of great strength, and having the binding members embedded within the structure in such manner as to effectively bind the parts together and at the same time provide a smooth wear surface.

Still other and further objects of this invention will in part be obvious, and will in part be pointed out in the specification hereinafter following by reference to the accompanying drawings wherein like charac-

ters are used to represent like parts throughout the several figures thereof.

Figure 1 is a view showing a cross section of the preferred form of my invention wherein the attaching members are entirely concealed within the structure. Fig. 2 is a detailed perspective view. Fig. 3 is a view of my invention illustrating attaching members passing through one face of the floor.

Steel being a good conductor of heat has made it necessary to provide the walls of steel cars with heat insulation. To make the heat insulation most effective it should be in the form of a continuous member or layer of the side wall or car floor. Furthermore in the construction of steel cars it is desirable that as much as possible of the car be formed of non-combustible material. For various reasons wood facing is undesirable, as for example, because of flying splinters in case of wrecks, and because of the liability of fire. Furthermore it is desirable, on account of high manufacturing cost, to eliminate wood construction from steel cars, because of the fact that steel working and wood working, being so different, it requires substantially two independent sets of workmen and two independent shops to produce a steel frame car having wood trimmings, as compared with the production of a steel car having no wood in its structure. To obviate difficulties various forms of side walls and floors have been produced, including metallic structures. A metallic side wall or partition is a good conductor of heat and this causes a car so constructed to be hot in summer and cold in winter, thereby requiring the use of some particular form of heat insulation, as a separate element. A metallic surface is not a desirable surface for a car floor, and a wood floor is not suitable for reasons above stated; and as a matter of fact under many conditions cars having any wood in their construction are absolutely prohibited from being used, as for example in subway systems. To solve the problem of car floors various types of constructions have been devised, and experience shows the preferred construction to be some form of fire proof composition supported by a metallic backing. A car floor or side wall is subjected to extreme vibrations and stresses in all direc-

tions. This being so, difficulty has been found in effectively securing the composite material to the metallic backing and at the same time also producing an effective heat 5 insulation.

My invention which will hereinafter be described in detail, relates to a car side wall, or more particularly to a car floor, wherein the car floor comprises a metallic 10 backing, carrying keystone anchoring members upon which rests a layer of heat insulation material and over which is secured, by submerged securing devices, a facing, a wear surface of composite material. The 15 heat insulation in my invention comprises a continuous diaphragm of heat resisting material interposed between the metallic backing, or steel supporting members with its filling material, and the facing or hard 20 wearing surface. This type of construction is very effective in preventing the transmission of heat between the opposite faces of the car floor or wall. The various parts are also so constructed and interlocked to 25 together that the heat insulating material forms a cushion which absorbs and takes up a large amount of the vibration stresses which heretofore have tended to break down structures of this character, and at 30 the same time provides a backing or sub-strata of sufficient elasticity to maintain the parts in their proper relation. Furthermore my invention includes the use of 35 means for tying together the keystone, or supporting strips, with the facing or wear surface in such a manner that the wear surface is substantially and effectively supported by the keystone members.

Referring more particularly to the drawings, the preferred form of my floor or partition includes a supporting element comprising a corrugated steel plate 1, preferably of the type known in the art as the "Keystone." The depending corrugations 45 are preferably filled, with an inelastic filler, such as cement 2, up to at least the level of the upper surface of the adjacent corrugations, thereby making the upper part of the sub-floor substantially a level surface 50 and providing the sub-floor with strips of supporting material of a keystone cross section interlocked in the metallic supporting element. Heat insulating material 4, is arranged to constitute the next layer of the 55 floor and is securely attached to the supporting element by suitable means, which tie the wear surface to the sub-floor. In my preferred form these means constitute screw bolts 5 which pass through the heat 60 insulation material and into nuts, which are embedded at predetermined intervals in the filler 2. The nuts may be of the cylindrical stepped type as is illustrated by the nut 6, or of the conical type as illustrated at 7, 65 Fig. 1. In both cases it is preferable that

the exterior of the periphery of the nut be provided with outstanding ribs 8 to insure against rotation of the nut when the bolt is being screwed in position. The heads of the bolts are seated in dished washers 9. Under 70 certain conditions ordinary screws without the nuts may be sufficient as a securing means, as for example, the screw illustrated as at 10, Fig. 1. By the foregoing specified arrangement it will be noted that the heat insulating material which may be hair felt, lime felt, flax felt, or other suitable material, is securely attached to the filler, or anchor bars, of cement or composition, laid in the keystone corrugations. The wear surface, 75 preferably composed of suitable cementitious composition 3, as for example, flexolith, is spread over the heat insulating material 4 in a plastic state and in such manner that it extends under the dished washers 9 so 80 that they are securely embedded therein. As the composition wear surface 3 hardens it securely grips the dished washers and it will be noted that the entire wear surface is then securely tied to the supporting element 85 by means of the submerged dished washers and the securing bolts or screws. It will be seen that this construction produces a car floor of substantially a unitary structure, composed of several elements tied together in such manner as to admit of sufficient flexibility and cushioning to prevent 90 injurious effects due to shocks or vibration. 95

Fig. 3 illustrates a modification of my structure, in which through bolts 11 terminate in valleys 12 and are provided with nuts 14, which are seated against flat washers 15. In this construction it will be noted that the composition wear surface is securely 100 tied to the supporting steel plate both by the keystone supporting ribs and by the through bolts 11, which pass through and support the valley portions of the sub-floor member. This construction is very strong and is more especially adapted for car side 105 construction where great strength against lateral vibrations is demanded. 110

Having thus described my invention what I desire to claim is:

1. A car floor structure of the character 115 described including in combination a corrugated metal plate, a cross section of the corrugations comprising truncated triangles, cement strips filling the corrugations to provide a substantially smooth surface, layers 120 of heat insulation material upon said smooth surface, a composition cement facing covering said heat insulating material, screw bolt fastening members passing through said heat insulating material and into said cement 125 strips, and anchoring devices within said composition cement facing and secured to said screw bolts to anchor said cement facing securely in position over the heat insulating material. 130

2. A car floor including in combination a corrugated metallic sub-floor, cement bars interlocked with said sub-floor and filling said corrugations to form a substantially smooth surface, a cushion of heat insulating material upon said smooth surface, a composition floor covering said heat insulating material, and fastening means having a portion submerged in said composition floor and another portion secured in said cement bars. 55
3. In a car floor in combination a metallic sub-floor provided with corrugations the cross section of which comprise truncated triangles; supporting strips filling the valleys on the upper side of said metallic sub-floor to produce substantially a smooth surface; heat insulating material covering said smooth surface, a composition cement floor resting on said heat insulation; and fastening means passing through said heat insulation, having one end thereof submerged in said cement filling and the other end thereof attached to said supporting strips. 60
4. A car floor including in combination a metallic sub-floor provided with corrugations adapted to form grooves having overhanging portions, supporting strips within said grooves and extending from wall to wall thereof, heat insulation material over said sub-floor, a composition wear surface upon said heat insulation, and fastening means extending from within said composition flooring and secured to said supporting strips. 70
5. A car floor including in combination a metallic sub-floor, supporting members interlocked with said metallic sub-floor, heat insulation comprising a cushioning material over said supporting members and said sub-floor, a composition wear surface over said heat insulation material, and interlocking members for securing said composition wear surface to said supporting members. 80
6. A car floor including in combination, a metallic sub-floor provided with grooves of dovetailed cross section, interlocking strips substantially filling certain of said grooves and extending from wall to wall thereof, a flat heat insulating diaphragm laid over said sub-floor and interlocking strips, a composition wear surface supported on said heat insulating diaphragm, and means secured to said interlocking strips and terminating within the wear surface to secure the metallic sub-floor and the composition wear surface together. 85
7. In a car construction in combination a corrugated sheet metal or floor member, means filling certain of said corrugations, a hard wearing surface, a continuous flat diaphragm of heat insulating material between the sheet metal member and the wear surface, and means to secure the said parts together. 60
8. In a car construction in combination a sheet metal or floor member, a hard wearing surface, a continuous flat diaphragm of heat insulation between said sheet metal member and the wearing surface, and fastening means interlocked with one surface of said steel supporting member and terminating beneath said wearing surface to secure the parts together. 70
9. In a car floor in combination a steel supporting sheet, an upper hard wearing surface, a substantially flat continuous diaphragm of heat insulation between the steel supporting sheet and the wearing surface to prevent the transmission of heat through the said floor, and fastening means interlocked with one surface of said steel supporting member and terminating beneath said wearing surface to secure the parts together. 75
10. In a car construction in combination a sheet metal member formed with corrugations, a filler filling the corrugations on one side of said sheet, a relatively thick cushion extending over the filler to provide a relatively elastic layer of material, a composition wear surface covering said cushion and securing means extending between said sheet and said wear surface and passing through said cushion. 90
